UNITED STATES PATENT OFFICE.

WILLIAM E. HICKS, OF ST. LOUIS, MISSOURI.

GOLF TEE AND TARGET.

Application filed October 26, 1925. Serial No. 64,719.

This invention relates to tees for golf balls and the like, and with regard to certain more specific features to a combined tee and target.

Among the several objects of the invention may be noted the provision of a portable tee which carries with it a target, whereby a given point of the object mounted thereon may be aimed at; the provision of a tee which before mounting an object thereon substantially indicates the future direction of flight of said object from the tee, if the object is struck under guidance of said target; the provision of an elongated, or round tee which seats a ball; the provision of such a tee as described which is light and which may be folded or otherwise put into a compact form for carriage thereof; the provision of a tee such as described which is easily opened for use; one which may be economically yet accurately made in quantities; and one which shall be neat and attractive in appearance.

Other objects will be in part obvious and in part pointed out hereinafter.

The invention accordingly consists of the elements and combination of elements, features of construction, and arrangements of parts which will be exemplified in the structure hereinafter described and the scope of the application of which will be indicated in the following claims.

In the accompanying drawings in which are illustrated various possible embodiments of the invention,

Fig. 1 is a side elevation of a preferred form of tee, showing the application of a golf ball thereto in dotted lines.

Fig. 2 is a plan view of the preferred form of tee and shows part of the ball in dotted lines;

Fig. 3 is a plan view of the preferred form of tee folded for carriage and shows in dotted lines a partially sprung position of the tee;

Fig. 4 is a side elevation of a form of the tee similar to the preferred form but constructed in a modified manner;

Fig. 5 is a plan view of Fig. 4, showing a portion of a ball in dotted lines;

Fig. 6 is a plan view of the device shown in Fig. 5, and shows in dotted lines a partially sprung position of the device;

Fig. 7 is a side elevation similar to Fig. 1, showing a modified form of the device;

Fig. 8 is a plan view of the Fig. 7 form, showing the device partially open;

Fig. 9 is a plan view of the Fig. 7 form, showing the device folded for carriage, and shows in dotted lines a partially sprung position thereof;

Fig. 10 is a side elevation similar to Fig. 1 of another modified form of the device;

Fig. 11 is a plan view of the device shown in Fig. 10, and shows a golf ball in dotted lines;

Fig. 12 illustrates the stretch-out view of the device shown in Fig. 10;

Fig. 13 is a side elevation of Fig. 12, and shows in alternate position, the shape of the material before packing;

Fig. 14 is a side elevation similar to Fig. 1, showing the application of another modified form;

Fig. 15 is a plan view of the device illustrated in Fig. 14, but illustrates it in a flattened position;

Fig. 16 is a side elevation of Fig. 15;

Fig. 17 is a top plan view of Fig. 7;

Fig. 18 is a vertical sectional view of another form, showing the application of a ball in dotted lines;

Fig. 19 is a plan view of the device of Fig. 18, showing the ball in dotted lines; and

Fig. 20 is a view showing the manner in which the last form may be packed or nested.

Similar reference characters indicate corresponding parts throughout the several views of the drawings.

Referring now more particularly to Fig. 1, there is illustrated at the numeral 1 a golf tee comprising a strip of cardboard or like flat material, which is adapted to be scored, corrugated, crimped, or otherwise prepared for bending along specific lines. This strip of material, with regard to its length, is laterally scored by means of score lines 3. The score lines 3 are preferably arranged vertically when the device is put into operating position. They are formed in parallel fashion and extend along the length of strip 1 for some distance as illustrated in Figs. 1 and 2.

At points such as shown at 5 and 7 of Fig. 2, the creases or score lines 3 are stopped and extensions 9 and 11 are provided integrally with said strip.

The extensions 9 and 11 may comprise one of any number of shapes such as may

suit the fancy of a designer of the device. However, the shape should preferably be such as to slope downwardly as the distance from the points 5 and 7 is increased, and there should be provided at the end of the sloping portions 13 ears or lugs 15.

After a strip of cardboard has been cut and scored as described, the portions 9 and 11 are bent backwardly one upon the other 10 and glued or otherwise fastened together flatly at all points except at the ears 15. It should be noted that the number of spaces between the score lines 3 is preferably made of an uneven order (although not necessarily so), so that one of the spaces such as space 17 shown in Fig. 2 becomes laterally formed with regard to the glued portions 9 and 11. The purpose of this will appear hereinafter. The structure so far described is also shown in solid-line position in Fig. 3. A score line 19 may, if desired, be provided between each of the ears 15 and the glued portions of the areas 9 and 11 (Fig. 1). The scored portions or areas 25 21 of the device are not glued as are the portions 9 and 11.

The device when made, is put into the form shown in Fig. 3 and is so packed in boxes or the like. A relatively large number 30 of the devices may be put into a small package so that they are not burdensome to carry about.

The cost of manufacture is low in so far 35 as the shapes of the strips 1 may be stamped from properly scored paper, cardboard or other material.

As stated, Fig. 3 represents the tee as 40 it rests in its carton at the time of sale. When one desiring to use a tee withdraws it from its container, the inherent tendency of 45 the device will be such as to cause it to immediately assume the general shape shown by dotted lines in Fig. 3. This is due to the fact that the score lines are formed on 50 the outside of the glued sheet of material.

In order to prepare the tee for use, it is 55 only necessary to hold it by means of the glued tail 23 formed by portions 9 and 11 and apply a pressure at the forward lateral area 17 in the direction of the arrow shown in Fig. 3. It will then automatically assume the substantially rounded shape shown in Fig. 2. It may then be placed on the ground 60 ready for use. The ears 15 will inherently spread apart somewhat to form a target 25, but if a wider target is desired, a downward pressure of a finger between the said ears 15 will serve to widen the target. The tee 65 may be set on the ground in the position shown in Fig. 1, or it may be inverted, if a player so desires. It is to be understood that an even number of spaces between score lines 3 may be provided, whereupon pressure is brought to bear on the most forward- 70 ly score line to open the device as described.

The tee is thus ready for use, and by placing a ball over the rounded cylindrical portion, said ball is properly adapted to be driven by one such as a golfer. It is obvious that the ball will always be automatically 70 positioned at a uniform correct predetermined height. It should be noted that the rounded shape of the device provides ample stability but prevents the lower edge of the ball from dipping too far down into the 75 hollow thereof. Hence the tee does not substantially interfere with the forward velocity of the ball as it leaves the tee. The light construction of the tee also prevents such interference.

In Fig. 1 the vertical arrow represents the approximate plane of sight of a player about to strike the ball with a suitable club or the like. It is evident that if said player has pointed the forward nose 17 of the tee in the direction he wishes to drive, that the target 25 will appear to him tangentially with regard to the ball at a point on the ball in which the ball should be struck in order to send it in the said direction. This statement holds under the assumption that the player is in proper playing position with regard to the ball. Hence the target indicates the proper place at which the ball should be struck in order to send it in the desired and predetermined direction. It also causes a player to assume a proper stance with regard to the ball.

The use of the target tends to prevent what is known as "topping" the ball, or 100 striking it high, whereupon it immediately bounds to the ground; a result not desired. This action is prevented or reduced by the fact that the player focuses his eyes upon the rearward tangential part of the ball where 105 it should be struck rather than upon the center of the top, where it should not be struck or struck at.

It is to be understood that a player with an idiosyncrasy such as requires him to 110 strike a ball to one side in order to cause it to drive ahead along the course, may yet take advantage of the target by offsetting the target a desired amount, that is, he may desire to apply a correction. The target 115 aids him in better applying the correction he must ordinarily make. However, any and all players, wherever they desire the target, have their focus lowered from the center of the top of the ball to the rear 120 thereof and hence, if for no other reason, their play is improved. Hence, in all cases the possible variables in the human equation are reduced.

The device, as a whole, is preferably made 125 of colored material, such as red, green, blue or other color, which will contrast well with the ball being played and whereby the target may be distinctly viewed.

It is to be understood that the device 130

may be left, after a drive therefrom (in that it is inexpensive) or it may be quickly picked up (if thought of) and carried in folded position to a new location. The folding operation requires mere pinching together of the portions 21 as the device is picked up.

Figs 4 to 6 show a modified form of the device in which the flat unglued strip of material of which the device is stamped and made, is put through a curling process. Hence the score lines may be dispensed with. The effect at the rounded, cylindrical portion is such as would be had by employing any infinite number of score lines, namely, a smooth curve. The effect of the curling operation is canceled at the glued portion in so far as the curling tendencies of the portions 9 and 11 are opposite. Hence a straight line is had at the tail 23. The target 25 is formed of ears 15 as before. Score lines 19 separate the ears from the portions 9 and 11. The target, in this modification, is shown at a higher elevation for purposes of illustration regarding flexibility of design.

Similar numerals are used in this modification to designate parts similar to parts of the preferred form. Accurately speaking, this modification involves chiefly constructional changes. As in the case of the first form, this form takes the solid line position shown in Fig. 6, when packed in a carton or the like. It springs to the dotted line position when taken from its carton in so far as it has been bent with its curl concave inwardly. Pressure on the nose 17^a (which is formed when the portions 9 and 11 are bent back) opens the device to its Fig. 5 position (see arrow, Fig. 6). Numerals 5 and 7 again indicate the line of demarcation between the portions 21 and the glued portions 9 and 11.

The remarks made regarding the use and advantages of the preferred form obviously apply to this form.

It may be profitable to remark that the curling may be done on any machine which will give a curled strip similar to one formed by drawing a strip between the thumb and a knife or like blade.

Figs. 7 to 9 and 17 illustrate another modified form of this device in which a strip of the said material is laterally (vertically in application) scored by incisions or scores 31, 33, 35 and 37. These scores form areas or portions 39, 41, 43, 45 and 47. The portion 47 forms a wing or flap which is glued to one end of the side portion 39. The portion 45 has cut therefrom, but permitted to be downwardly hinged thereto, a target arm 49 carrying a target 51.

In Fig. 9, the score line 33 is represented as having been pushed inwardly between portions or walls 39 and 45 and said walls

brought together. The target arm 49 and the target 51 thereon are within the notch from which they were cut. This Fig. 9 solid line position comprises the folded shape of the modified device when packed in a carton. It takes less space than the preferred form.

When the device is removed from its container or carton it assumes the dotted line spring position shown in Fig. 9. A score line or crease 53 may or may not be provided at the juncture between the target arm 49 and the wall 45.

By inserting or wedging a finger in between the walls of the sprung device, it may readily be caused to take the formation illustrated in Fig. 8. The rear wall 45 is somewhat bent at a point beneath the target arm 49 because the section thereof has been weakened by cutting out said arm 49 and the target 51. While the finger or the like is being inserted as described, the said arm 49 and target 51 may be drawn downwardly, as illustrated.

Next, by continuing the above described operation the position illustrated in Fig. 17 is reached. When the finger is withdrawn, the walls 43 and 41 remain substantially in a single plane. In so far as the rear wall 45 is not scored, it tends to revert to a straight line position. The wall 39 is flat. Hence there is formed a triangle (isosceles preferably). The target arm 49 is formed on the wall 45 opposite the apex score 31 of said triangle. Obviously, if a ball or the like is mounted on or cradled in the triangular piece or cylinder, the target 51 will indicate to an observer above, where the ball should be struck in order to drive it ahead in the direction pointed to by the apex 31 of the triangle. It is to be understood that the target arm 49 is long enough to permit projection of the target 51 from the ball in substantially vertical or near vertical projection. The top edge of the target 51 may, before cutting, have formed the top edge of wall 45 or it may not have done so, depending upon the relative heights of tee and target arm required for a given player and/or ball. The rear wall 45 is illustrated as being bent slightly rearwardly in Fig. 17. This is the result of the weight of the ball tending to slightly bend the wall at the point of cutting of the target arm.

The advantages regarding the setting, aiming and striking either the ball and or tee, stated in regard to the preferred form and the first modified form hold for this form.

In order to fold this form for carriage, after use, it is only necessary to press the score line 33 inwardly, raise the target arm 49, and clamp the walls 39 and 45 together. This involves passage through the Fig. 8 position, through the dotted Fig. 9 position, to the full line Fig. 9 position.

Figs. 10 to 13 show another modified form of the elongated tee which is readily and more cheaply made and may or may not employ the target feature. Of course any 5 of the forms may dispense with the target feature but this one is illustrated without it.

This modification comprises a preferably 10 rectangular strip 55 of cardboard or the like stamped or cut with notches 57 and 59 formed on opposite sides thereof, near opposite ends. (See solid lines Figs. 12 and 13). The notches are of a length substantially one-half that of the width of the 15 strip 55. This strip 55 is then, or may have been before cutting, curled (as already described) so that it tends to assume the alternate position shown in Fig. 13.

Then by bringing opposite ends of the 20 strip 55 together and registering and interlocking the notches 57 and 59, the position illustrated in Figs. 10 and 11 is assumed by the device. This is somewhat drop-shaped in section. The portions 61 and 63 form rearwardly extending wings which, if extended, will form a target. In 25 this case the ball is to be struck between the projections of the indicators or wings 61 and 63.

30 The advantages of the foregoing forms pertain to this one, with the advantage here of cheaper construction. It is thought that the double twisting required to shape this one may cause it to be somewhat less 35 accurate than the other. Its compactness when not interlocked for play is self evident.

Another form of the device is illustrated 40 in Figs. 14 to 16. Here a preferably metallic sheet 65, such as of sheet lead or the like, is stamped rectangularly or of other shape. This shape has more or less centrally cut or stamped therefrom a cross-shaped or cruciform area 67. The area 67 45 comprises a central rectangular or like opening 69 from the corners of which extend radiating openings 71. The openings 71 become narrower as they approach the central opening 69.

50 To put this last form into operative position for play, the finger portions 73 formed between the slots or openings 71 are bent upwardly on lines such as 75. The lines 75 are not necessarily specific score 55 or crease lines but they may be. The ball to be played is rested on the top edges of the portions 73. The tapering feature of the slots 71 permits of a relatively small opening 69 for a given size of slots and a given angle at portions 73. Hence the ball 60 is not permitted to unnecessarily dip too far down below the upper edges. The elongated feature of the opening 69 gives a longitudinal track-like effect from which the ball 65 may be effectively driven. If desired,

the opening need not be made elongated. The fact that the opening 69 is relatively small would permit of its being made square or of other shape without seriously blocking the flight of the ball. It is to be understood that the flat portions of the piece 65 may be formed as a target to be visible tangentially with regard to the ball.

It is obvious that the described construction in all forms insures beside the advantages enumerated, uniform height for teeing of balls; prevents soiling of hands as when using sand tees or those which require a piercing of the soil therebeneath; prevents blocking the flight of a ball when struck; insures accuracy such as tees which are roughly torn from a perforated strip cannot give; and is handy, light and of such low intrinsic value as to cause little concern over the loss of one tee in so far as many of them may be carried at little cost and/or inconvenience. The construction also has the advantage that it can be used under all turf conditions. For instance, wooden or metal tees which are pushed into the ground are almost rendered useless when the teeing ground is baked hard by the sun or softened by rains. This type of pushed-in tee also tends to block the forward flight of a ball while the present one itself moves, instead of tending to block the struck ball.

One more modification of the device is illustrated in Figs. 18 to 20. This comprises a cup-shaped piece 81 formed by molding, stamping, or otherwise forming fibrous material or material such as bakelite and the like. The cup-shaped piece 81 is formed with an opening 83 in the top thereof. The ball to be driven is seated on this opening. The broad base provides steadiness.

For purposes of packing, the cup-shaped pieces may be nested, as illustrated in Fig. 20. These pieces are light and neither block the flight of the ball nor make a clumsy package to be carried. They may be provided in various conoidal forms and may have a target formed therewith, if desired.

In view of the above, it is believed that the various features of this invention will be clear without further elaboration, and it will be seen that with the apparatus herein described, the several objects of the invention are achieved and other advantageous results attained.

As many changes could be made in carrying out the above construction without departing from the scope of the invention, it is intended that all matter contained in the above description or shown in the accompanying drawings shall be interpreted as illustrative and not in a limiting sense.

I claim:

1. A tee comprising a strip of pliable material, lateral score lines thereon, flat portions at the ends of the strip adapted to be

held together and a target formed at the flat portions.

2. A tee comprising a strip of pliable material, lateral score lines thereon, flat portions at the ends of the strip adapted to be held together whereby the scored portions are cylindrically formed and a target formed at the flat portions. 20

3. A tee comprising a strip of pliable curled material, flat portions at the ends of the strip adapted to be held together and a target formed at the flat portions. 25

4. A tee comprising a strip of pliable curled material, flat portions at the ends of the strip adapted to be held together whereby the unfastened curled portions are cylindrically formed and a target formed at the flat portions. 30

5. A tee comprising a strip of pliable ma- 35

terial, lateral score lines thereon whereby two walls and a centrally scored wall are formed and a flap on one of said two walls adapted to be fastened to the other of said two walls, and a target hinged to the said first named unscored wall.

6. A tee comprising a strip of pliable material, lateral score lines thereon whereby two walls and a centrally scored wall are formed and a flap on one of said two walls adapted to be fastened to the other of said two walls, and a target partially cut from and hinged to the said first named unscored wall.

In testimony whereof, I have signed my name to this specification this 23d day of October, 1925.

WILLIAM E. HICKS.
